UNITED STATES PATENT OFFICE.

MICHAEL A. KERR, OF BURKBURNETT, TEXAS; ASSIGNOR OF ONE-HALF TO ADOLPH CHANOWSKY, OF FORT WORTH, TEXAS.

PUMP.

Application filed February 11, 1922. Serial No. 535,687.

To all whom it may concern:

Be it known that I, MICHAEL A. KERR, a citizen of the United States, residing at Burkburnett, in the county of Wichita and State of Texas, have invented certain new and useful Improvements in Pumps, of which the following is a specification.

My invention relates to pumps and more particularly to working barrels, packing and packing chambers; and the object is to provide pumps with packing and packing chambers therefor in combination with working barrels in which many parts, such as packing cups, and other easily worn parts, are eliminated, and to provide packing chambers in which the packing will be automatically maintained, and to provide packing and packing chambers and plungers which will not be effected by sand or dirt and other grinding or cutting particles and also eliminate the frequent pulling of rods to change cups, and to provide pumps which will be highly efficient in pumping oil and other liquids. One of the advantages of the improved pump is that the cutting of the oil will be largely prevented. Another advantage is that the pressure of the liquid usually attendant upon the pulling of the plungers with their cups is prevented and the consequent vacuum caused by lifting of such cups is prevented. Other objects and advantages will be fully explained in the following description and the invention will be more particularly pointed out in the claim.

Reference is had to the accompanying drawings which form a part of this application.

Fig. 1 is a vertical section of a portion of a working barrel and a packing chamber and the packing therein. Fig. 2 is a broken vertical section, illustrating the continuation of the pumping barrel and casing shown in Fig. 1. Fig. 3 is a broken vertical section, on a smaller scale, of the casing shown in Fig. 2 and showing a check valve therein.

Similar characters of reference are used to indicate the same parts throughout the several views.

This pump is provided with a packing chamber 1 which has the lower end swaged to reduce the same to the size of the casing 2 which is connected thereto by a collar 3. A swaged collar 4 is screwed on the upper

end of the packing chamber 1 and this reducer 4 is connected to the casing 1 by a collar 5. The working barrel 6 operates through the packing chamber and through the packing 7 therein. A packing supporting ring 8 is mounted in the lower end of the packing chamber and supported therein by the swaged end 9 of the packing chamber. The packing 7 is placed in the chamber 1 about the working barrel 6 and a packing-compression ring 10 is placed on top of the packing 7. Any pressure by liquid on the ring 10 will be transmitted to the packing 7. The pressure on the packing 7 will thus be automatically maintained. A cup-shaped cavity 11 is formed in the upper end of the ring 10 about the barrel 6 to aid in forming a seal about the barrel by maintaining liquid about the barrel during operation. The approximately funnel shaped cavity 11 cooperates with the tapered member 12 of the working barrel to make the projection of the working barrel through the packing 7 easily accomplished. The pressure on the packing 7 will expand the packing against the barrel 6 and against the wall of the chamber 1. The lower end 12 of the working barrel 6 is reduced to make the barrel easily operative through the packing chamber. The lower end of the working barrel is connected to the main barrel by a screw joint 13 and a valve seat 14 is formed in the upper end of the section 15 of the pump barrel. A check valve 16 is provided for the pump barrel and is adapted to engage the seat 14 on the upstroke of the barrel. The working barrel section 15 is provided with openings 17 therethrough for relieving the pressure of the liquid in the casing 2 and in the reducer 4 about the barrel 6. When the openings 17 pass above the ring 10, the liquid in the casing 2 and the reducer 4 will pass down inside the member 15 and thus relieve the pressure on the barrel. A coupling 18 connects the intake pipe 19 with the casing 2. A valve 20 and cage 21 therefore are provided and a pipe 22 forms a communication between the intake pipe 19 and the casing 2 through the valve seat of valve 20. In operation the liquid passes up through the intake pipe 19, thence through the pipe 22 and past the valve 20 into the casing 2. The working barrel 6 with reduced end 12 takes the liquid from the casing 2. Various changes in the sizes, construction and

arrangement of the several parts may be made without departing from my invention.

What I claim, is,—

A pump having a casing in sections, an enlarged packing chamber having a swaged lower end for connection with said casing, packing in said chamber, a ring supporting said packing and resting on the swaged portion of said chamber, a ring compressor for said packing having a cup-shape on the upper side about the opening therethrough, a reducer connecting the upper end of said packing chamber to said casing, a working

barrel in said casing operating through said packing and having a tapered valved section detachably connected thereto, said valved section having an integral valve seat therein and having perforations below said seat for relieving pressure on said working barrel when said barrel passes above said packing, and a valve adapted to engage said seat.

In testimony whereof, I set my hand, this 6th day of February, 1922.

MICHAEL A. KERR.
